UNITED STATES PATENT OFFICE

WILLIAM E. RUPLEY, OF LOS ANGELES, CALIFORNIA, ASSIGNOR TO WESTERN PIPE & STEEL COMPANY OF CALIFORNIA, OF SAN FRANCISCO, CALIFORNIA, A CORPORATION OF CALIFORNIA

STOVEPIPE CASING

Original application filed September 26, 1925, Serial No. 58,951. Divided and this application filed August 5, 1926. Serial No. 127,354.

This invention relates to stove pipe casing and refers more particularly to a stove pipe casing composed of a plurality of concentric tubular sections which are rigidly welded one to the other at their connecting joints.

5 This application is a division of my pending application for stove pipe casing and method and apparatus of forming the same, filed September 26, 1925, Serial No. 58,951.

10 Stove pipe casing is employed in the sinking of wells for the recovery of either water, gas or oil. Such stove pipe casing is driven or lowered into the hole formed for the well. When in the proper position, the stove pipe 15 casing is set and remains as a permanent part of the well. In order to prevent the collapse of such a stove pipe casing, the same must be of great strength and as the same is a permanent part of the well, must be of 20 great durability.

Many types of stove pipe casing are now in use which are for the most part of expensive construction or are of insecure manner of connection of the sections one to another so 25 that the same "part" during the driving of the casing.

It is, therefore, an object of this invention to provide a stove pipe casing of any durable construction and of great strength so that the 30 same will withstand the driving of the same and will be extremely adaptable for use as a permanent part of a well.

Another object of this invention is to provide a stove pipe casing having a practically 35 uniform exterior contour throughout its length so that the same will not "hang up" during the driving of the same.

Other objects and advantages of this invention will be apparent from the following 40 detailed description of a preferred embodiment thereof as illustrated in the accompanying drawings.

In the drawings:

45 Figure 1 is a side elevation of a stove pipe casing embodying this invention.

Figure 2 is a sectional side elevation thereof.

50 Figure 3 is a side elevation of a fragment of stove pipe embodying this invention, illus-

trating the manner of assembling the sections thereof.

In the preferred embodiment of this invention, illustrated in the accompanying drawings, 1, 2 and 3, illustrate a series of tubular sections of sheet steel which tubular sections 1, 2 and 3 are disposed within a plurality of outer tubular sections 4, 5 and 6. The tubular sections 1, 2 and 3, and 4, 5 and 6, are from three feet up in length, depending 55 upon that desired by the manufacturer constructing the stove pipe casing. The ends of the tubular sections 1, 2 and 3 are abutted and the ends of the sections 4, 5 and 6 are abutted between the abutted ends of the inner sections 1, 2 and 3 so that the joints formed in 60 the casing are staggered.

The joints between the inner sections are electric or acetylene welded preferably with a 65 butt-weld so that a welded joint is made that secures the ends of the sections together and secures the ends of the sections to the outer section overlaying the same. Such a welding connection is illustrated at 7 wherein 70 the abutting ends of the tubular sections 1 and 2 are welded together and the two sections 1 and 2 are welded to the outer section 75 4.

A similar weld is formed between the abutted ends of the outer sections and the inner 80 casing, for example, the adjacent ends of the sections 4 and 5 are welded together and to the inner casing as illustrated at 7a.

The tubular sections 1, 2 and 3 are of slightly less exterior diameter than the tubular 85 sections 4, 5 and 6 so that the same will fit within the interior of the sections 4, 5 and 6. The tubular sections comprising this stove pipe casing are formed of sheet steel and are lap-riveted as illustrated at 8 and 9.

90 Each section or stand of stove pipe casing is formed of a plurality of concentric tubular sections and may be of any desired length and these stands are in practice built up to about twenty-eight or thirty feet. The end 95 of either tubular section 10 projects from the end of the outer end tubular section 11 approximately one-half its length as illustrated in Figure 3. On a second section or stand of casing, the end outer tubular member 12 pro- 100

jects approximately one-half its length beyond the end of the inner tubular member 13. A plurality of perforations 14 are formed around the circumference of the outer tubular member 12 immediately above the end of the tubular section 13. In assembling two stands or sections of stove pipe casing when the same are in position to be lowered in a well, the end of the tubular section 10 is fitted into the end of the tubular section 12 with the end 15 thereof in abutment with the end 16 of the tubular section 13. A welder then spot-welds through the perforations 14, welding the tubular section 10 to the tubular section 13 and to the tubular section 12 much in the same manner as is illustrated at 7 except that in case of the welding through the perforations, the weld connecting the three tubular sections is not continuous as illustrated at 7. The welder then welds the sections 11 and 12 together at their ends and to the inner section 10 to form exactly the same manner of welded connection as is illustrated at 7. By this means, the stands or sections of stove pipe casing are secured together in approximately the same manner and have approximately the same strength as the connections formed between such sections as 1, 2 and 4.

An elevator 17, employing slips 18 is illustrated in Figure 1 as gripping the outer surface of such a stove pipe casing. The entire length of the stove pipe casing may be "picked" in the manner illustrated in the patent granted to Morgan L. Sweeney, on September 11, 1917, Serial No. 1,240,098.

Having fully described a preferred embodiment of this invention, it is to be understood that I do not wish to be limited to the exact details herein set forth which may obviously be varied in detail without departing from the spirit of my invention as set forth in the appended claims.

I claim:

1. A stove pipe casing comprising a plurality of inner tubular sections concentric within a plurality of outer tubular sections and welded staggered joints formed at the abutted ends of the said sections and welding the said sections to the opposite concentric member.

2. A stove pipe casing comprising a pair of concentric casings, each of which casings being composed of a plurality of tubular sections welded at their abutted ends to each other and to the opposite concentric casing intermediate joints formed in the opposite casing.

3. A stove pipe casing comprising a concentric casing, each stand of which casing comprises a plurality of tubular sections welded together at their adjacent ends and to the opposite concentric casing intermediate the joints thereof, the ends of the end inner tubular member projecting out from the strand at one end and the end of the end outer tubu-

lar section projecting out from the stand at the opposite end, the projecting inner tubular section of one stand being adapted to be inserted within the projecting end of the outer tubular section of a second stand and a plurality of perforations formed in the projecting end of the outer tubular section adjacent the end of the last inner tubular section at that end of the stand through which perforations the abutting ends of the inner tubular sections are welded together and to the outer casing.

4. A pipe casing comprising a plurality of inner tubular sections within a plurality of outer tubular sections, the abutted joints of the inner sections being staggered in relation to the abutted joints of the outer sections, the abutted edges of said sections being welded together and to the opposite concentric sections.

Signed at Los Angeles, California, this 20th day of July, 1926.

WILLIAM E. RUPLEY.
